UNITED STATES PATENT OFFICE.

FRANK E. TROUTMAN AND CHARLES H. CHRISTIE, OF BUTLER, PENNSYLVANIA.

GRINDING AND POLISHING TABLE.

Application filed October 3, 1923. Serial No. 686,347.

Our invention relates to tables for use in grinding and polishing plate glass and for similar purposes.

The object of our invention is to provide a grinding or polishing table composed of wheeled sections adapted to run upon tracks and provided with means for insuring that the upper surfaces of the several sections shall be at precisely the same level when they are brought to the grinding or polishing position.

Plate glass has heretofore been ground upon large rotary tables which are costly and expensive in operation and which require much labor for the purpose of lifting the glass upon the table and removing the glass therefrom. It has been proposed to substitute for these rotary tables rectangular tables mounted upon wheels so as to run in series upon tracks for the purpose of rendering the manufacture of plate glass more nearly a continuous operation. Such sectional grinding tables have the disadvantage that no matter how carefully the tables and tracks are constructed, the joints between the tables are more or less uneven, the rear edge of one table being slightly above or below the front edge of the next table. Such differences in the height of the tables interfere with the grinding and polishing operations because the plates or sheets of glass will not be engaged properly by the grinding implements.

According to our invention we insure that all the tables of a series of grinding or polishing tables shall be at a constant height and without uneven joints, when the tables are brought to a grinding or polishing position. In one embodiment of our invention we accomplish this result by causing one end of each table to support the adjacent end of the following table the trucks which carry the tables being so arranged that at the grinding position the wheels at the supported end of each table are above the auxiliary tracks. The rear edges of the tables may be provided with recesses or ledges for receiving the front edges of the following tables in such a way that the upper surfaces of the tables are in exact line with each other when the tables support one another in the overlapping manner just described; or the tables may be arranged to connect with one another by means of dowel pins or the like.

The trucks of the table sections are pref-

erably provided with two sets of wheels, the bottom level of one set of wheels being slightly higher than the bottom level of the other set. One set of wheels, which we term the service wheels are intended to run upon ordinary tracks, and are used in shifting the tables and in bringing the tables to the grinding or polishing positions. The other set of wheels may be called the auxiliary wheels, and are adapted to run upon auxiliary tracks which lead past the grinding or polishing positions. When the front of each table is to be supported on the rear ledge of the preceding table the front auxiliary wheels should be somewhat smaller or mounted at a slightly higher elevation than the rear auxiliary wheels, so that when the overlapping edges of the tables are brought together the front auxiliary wheels are raised above the auxiliary track and do not interfere with the proper matching of the tables. In a similar way the rear end of each table may be supported on a ledge at the front of the next following table, in which case the rear auxiliary wheels should be of smaller diameter than the front auxiliary wheels.

The accompanying drawing shows the arrangement in which the front end of each table is supported on the rear of the next preceding table. As each table arrives at the auxiliary track its front service wheels run off from the service track and the front end of the table is thereby caused to descend into a seat formed in the rear end of the preceding table. Each table following the first is thus supported, while at the grinding position upon its rear wheels and upon the rear end of the next preceding table. Therefore the upper surfaces of the tables will be at the same level even though the tracks may be somewhat irregular. The first table of the series is supported at the grinding position upon both the front and rear auxiliary wheels and the front of the first table is therefore very slightly below its rear end. This trifling inclination thus given to the first table is so small as to be negligible. If it is desired to avoid even this slight inclination of the first table, an auxiliary table or car may be provided to precede the first table and support its front end, in which case only the rear sets of auxiliary wheels need be provided on the tables.

In the accompanying drawing Fig. 1 is a side elevational view of a series of grind-

ing or polishing tables constructed and arranged according to our invention; Fig. 2 is a similar view showing the tables advanced somewhat farther to the left; Fig. 5 5 is a plan view of a portion of the construction shown in Figs. 1 and 2; Fig. 4 is a rear elevational view of one of the table sections; Fig. 5 is an enlarged fragmentary sectional view showing the manner in which 10 the sections co-operate with each other, and Fig. 6 is a fragmentary section taken substantially on the line 6—6 in Fig. 2.

In the drawing the numerals 2 indicate a series of rectangular grinding or polishing tables having front wheels 3 and rear service wheels 4 adapted to run upon service tracks 5. In Figs. 1, 2 and 3 the tables are considered as moving to the left. The tracks 5 end at 6 and in prolongation of the tracks 5 is a pair of auxiliary tracks 7 which are preferably at a somewhat higher elevation than service tracks 5 and are of a gauge either narrower or wider than the tracks 5. The auxiliary tracks 7 conduct 25 the tables 2 to suitable grinding or polishing mechanism, not shown. The shafts 9 which carry the service wheels 4 of each table section also carry pairs of auxiliary wheels 10 which are of proper diameter and 30 properly spaced to run upon the auxiliary tracks 7 while the rear wheels 4 are still resting upon the tracks 5. The treads of the front auxiliary wheels 10 are preferably about one-eighth of an inch higher than the treads of the rear wheels 10, so that when 35 passing to the auxiliary tracks the front end of the rear car will tend to descend to a lower level than the rear end of the preceding car.

40 At the rear edge of each of the table sections 2 is a ledge 11 of proper size and shape to receive and support a projection 12 which extends forward from the front edge of the next succeeding table. The vertical height 45 of the projection 12 is made exactly the same as the distance between the top of the ledge 11 and the top of its table, so that when the projection 12 rests upon the ledge 11 the upper surface of the two tables will 50 be at the same level as shown at the left of Fig. 2.

55 For the purpose of preventing the tables from relative lateral movement when they are in engagement, each of the ledges 11 is provided with a V-shaped notch 13 which receives a correspondingly shaped projection 14 formed on the under side of the projection 12 of the following table. If desired, the projections 12 may be provided with recesses and the ledges 11 with projections, or other equivalent means may be provided 60 for interlocking the meeting portions of the tables so as to prevent relative lateral movement.

65 The vertical meeting surfaces of the ta-

bles may be provided with strips of rubber or other cushioning material indicated at 16 for taking up the shock when the tables engage each other. Such cushioning strips may be provided on one or both of these meeting surfaces as may be desired.

Another feature to which attention is directed resides in the provision of upwardly extending ribs 2^a which serve as retaining walls to prevent the plaster and sheets of 75 glass from sliding off the table. Heretofore holes have been drilled adjacent to the edges of casting tables for the reception of pegs or pins whereby the plates of glass are held in 80 position upon the table top. These pegs become worn down and have to be replaced, or become broken and the holes have to be re-drilled, and also the plaster with which the 85 tables are usually covered oozes over the edges of the tables, drops to the floor and causes litter, besides which the continuity of the plaster surface on which the glass is supported is destroyed, and the glass imperfectly supported at some points. These objections are avoided by the use of the ribs as 90 shown. These ribs may be either formed integrally with the table top or consist of strips secured thereto by screws, bolts or the like.

95 In the operation of the grinding or polishing tables constructed in the manner described above, the tables are covered with plaster in the usual manner to a thickness preferably less than the height of the ribs above the table top, and the sheets or plates of glass are laid on the tables, suitably by 100 means of the suction lifting apparatus described and claimed in the copending application for Letters Patent of Troutman and Christie filed January 20, 1923, Serial No. 613,949, now Patent No. 1,535,064 dated April 1, 1925. When the tables are thus prepared, they are pushed along the service tracks 5 with the front edge of each table slightly above the level of the rear edge of the preceding table until the front wheels 3 105 of the table run off from the ends 6 of the service tracks 5 whereupon the front end of the table descends until its projection 12 rests upon the ledge 11 of the preceding table. Before the rear wheels 4 have reached 110 the ends 6 of the service tracks 5 the auxiliary wheels 10 have run upon the auxiliary tracks 7 and are ready to support the table when the rear wheels have run off from the service tracks 5. The tables are advanced 115 to the grinding or polishing apparatus which may be of any suitable kind, as indicated at 120 17 and 18, and after the grinding or polishing operation is completed the cars are advanced still further and may again be run upon ordinary service tracks such as the tracks 5 so that the tables may again be 125 handled individually for the purpose of turning the glass if necessary and preparing the tables for the next grinding operation. 130

It will be evident that the principles of our invention may be carried out by reversing the ledges 11 and the projections 12 and making the front end of each table support the rear end of the preceding table, the arrangement in such case being similar to that shown in Fig. 1 in which it may be assumed that the cars in Fig. 1 are advanced to the right instead of to the left, with the arrangement of the tracks reversed. Various other changes in the construction and arrangement of parts may be made without departing from our invention, the scope of which is set forth in the appended claims.

15 We claim as our invention:

1. Apparatus for grinding and polishing flat glass comprising two sets of tracks arranged in alignment with each other and of different gages and at different heights, and 20 a plurality of grinding or polishing tables each having front and rear wheels adapted to run upon one of said tracks and having auxiliary wheels adapted to run upon the other track, the said table having means for 25 causing the end of each table adjacent to said auxiliary wheels to support the end of an adjacent table when the said tables rest upon said auxiliary track.

2. Apparatus for grinding and polishing flat glass comprising two sets of tracks ar-

ranged in alignment with each other and of different gages and of different heights, and a plurality of grinding or polishing tables having front and rear wheels adapted to run upon one of said tracks and having auxiliary 35 wheels adapted to run upon the other track, each of the said tables having a ledge projecting from one end thereof and a projection at the other end adapted to rest upon the ledge of a similar table, means for preventing relative lateral movement of the associated ledges and projections, and cushioning means, associated with said ledges and projections, for cushioning the shock of engagement of the said tables. 40

3. Apparatus for grinding or polishing flat glass comprising a plurality of relatively movable associated tables, a projection on one of said tables, and a horizontally disposed engaging surface on an adjacent portion of another table, the riding support for said tables being arranged to bring said projection to rest upon said engaging surface, to maintain the surfaces of said tables in 50 horizontal alignment. 55

In testimony whereof we, the said FRANK E. TROUTMAN and CHARLES H. CHRISTIE, have hereunto set our hands.

FRANK E. TROUTMAN.
CHARLES H. CHRISTIE.

DISCLAIMER.

1,610,184. —*Frank E. Troutman and Charles H. Christie, Butler, Pa.* GRINDING AND POLISHING TABLE. Patent dated December 7, 1926. Disclaimer filed May 11, 1928, by the patentees.

Hereby enter this disclaimer to that part of the claim in said specification which is in the following words, to wit:

“3. Apparatus for grinding or polishing flat glass comprising a plurality of relatively movable associated tables, a projection on one of said tables, and a horizontally disposed engaging surface on an adjacent portion of another table, the riding support for said tables being arranged to bring said projection to rest upon said engaging surface, to maintain the surfaces of said tables in horizontal alignment.”
